UNITED STATES PATENT OFFICE.

DILLON HOFFMAN AND FRANK EASTON, OF NEW YORK, N. Y.

LOCK.

1,407,538.

Specification of Letters Patent. Patented Feb. 21, 1922.

Application filed January 11, 1921. Serial No. 436,469.

To all whom it may concern:

Be it known that we, DILLON HOFFMAN and FRANK EASTON, both citizens of the United States, and residents of the city of New York, borough of Manhattan, in the county of New York and State of New York, have invented a new and Improved Lock, of which the following is a full, clear, and exact description.

10 Our invention relates to a lock, and aims to provide a device of this character more particularly adapted for use in connection with an electrical circuit.

In connection with electrical circuits, and more particularly the ignition circuit, of an automotive vehicle, it is a well appreciated fact that it has been customary to provide a switch which may be opened and closed only upon the actuation of a lock.

20 This has offered certain objections in that an operator has quite often failed to actuate the lock so that an unauthorized person would be capable of closing the circuit and operating the vehicle. Also upon the loss of the key it has been impossible for the authorized operator to close the circuit without demolishing the lock.

Entirely aside from the foregoing it is also well understood that numerous thefts of 30 automotive vehicles have occurred where the lock had been properly actuated, incident to the fact that a thief who was expertly acquainted with the manipulation of locks could disassemble or otherwise mutilate the 35 same to close the circuit without any one becoming aware of the fact that an unauthorized person was endeavoring to accomplish this purpose.

Having the foregoing in mind, we have 40 constructed a lock more particularly adapted for use in connection with the ignition circuit of an automotive vehicle, but not necessarily limited to this adaptation, and by means of which it will not be necessary for 45 an operator to utilize a key to complete closing and opening of the circuit, although this may not be accomplished by an unauthorized person.

A further object of our invention is the 50 provision of a device of the type specified in which the parts may be moved to necessitate a different manipulation of the lock to effect a closing of the circuit.

A still further object of our invention is 55 the construction of a lock in which an alarm

will be given upon an unauthorized person endeavoring to manipulate the same.

Another object of the invention is the provision of means whereby an unauthorized person will be unable to cause a cessation of 60 operation on the part of the alarm subsequent to the same having once been actuated, and in which it will also be impossible to permit of the circuit being closed by any person other than the proper operator, after 65 the parts of the lock had once been improperly operated.

Further objects of our invention will appear in the annexed specification and drawings, which latter present one practical embodiment of our invention, and in which—

Figure 1 is a front view of a lock embodying our improved construction, and showing the cover removed therefrom.

Figure 2 is a rear view thereof.

Figure 3 is a sectional side view taken along the line 3—3 in the direction of the arrows in Figure 1.

Figure 4 is a diagrammatic arrangement of the parts showing the position of the 80 circuits, and

Figure 5 is a face view of the completed device.

In these views the reference numeral 10 indicates the casing of any desirable contour, presenting a face normally closed by means of any suitable cover 11, which is hingedly associated with a casing as at 12, and is normally retained in closed position by any suitable type of lock 13.

90 In the embodiment illustrated, and in view of the fact that we utilize a substantially circular casing it will be noted that the cover 11 carries a suitable number of annular series of buttons 14, each of which may bear 95 any desirable indicating marking for a purpose hereinafter more fully specified.

It will be noted, reference being had to Figure 3, that each of the buttons 14 is slidably associated with the cover 11, and a 100 spring 15 serves to normally press the buttons outwardly, such movement being limited by any suitable means, such as the head 16 of the pin 17 forming a fixed portion of each of the buttons 14.

105 Referring now more particularly to Figure 1, it will be seen that a plurality of contact rails 18 are arranged within the casing 10, certain of said contact rails underlying different series of buttons 14. Thus, 110

assuming that a traveling contact point is slidably arranged upon certain of the rails 18, these rails carry current, and the casing being grounded a projection on the part of 5 one of these buttons will result in a flow of current through the same, the contact member, and so into the rail, or vice versa.

Referring now more particularly to this contact member, it will be seen, reference being had to Figure 3 that the same preferably includes a clip portion 19 capable of slidable engagement with one of the rails, a grasping portion 20 permitting of its being manually shifted, and insulation 21, which 10 serves to prevent the flow of current from the body portion of the traveling contact point into certain of the rails with which it is associated.

In the embodiment illustrated, it will be 20 noted that we have shown a pair of solenoids 22 and 23 respectively, at points underlying the contact rails 18. Each of these solenoids serves to actuate armatures 24 and 25, respectively, which latter are normally projected from within the body of the solenoid by means of springs 26.

Attention being had to Figure 4 it will be seen that the armature 24 carries an arm 26, which latter cooperates with normally closed 30 switches 27 and 28, to effect a closing of the same, which armature 25 is provided with an arm 29 and serves to bridge the points 30 upon the solenoid 23 being actuated.

In the embodiment illustrated, it will be 35 noted that a suitable source of current 31 has one of its leads grounded as at 32, the second lead extending to the solenoid 22 and thence to the outer and inner tracks 18. Also each of the buttons being of metal, and associated 40 with the casing 10, is grounded, by virtue of the grounding of the latter, indicated at 33. The lead extending from the source of current 31, is provided with a branch 34, having the convolutions of the solenoid 23 arranged 45 in series therewith. Thence this lead extends to one of the points of the switch 27, the opposite portion of said switch being connected in the form shown, to the secondary rail 18.

50 Also with a view of providing a suitable alarm, it will be noted that we may utilize an electrically actuated bell, or other suitable device.

With a view of providing a suitable source 55 of actuating current for this signal, the feed lead of the source of current supply 31, is provided, as has been indicated by the reference numeral 36, and arranged in series with this latter branch is the signal 35, the branch 60 extending thence to one of the points of the switch 28, the second point of which is grounded as at 37.

Assuming now that the traveling contact point embracing the clips 19, has been moved 65 to a position which has been noted by the op-

erator, it will be seen that upon pressing the proper button 14, that contact will be established from the source of current supply 31, through the main lead 38, thence through the branch lead 34 through the solenoid 23 thence 70 through the closed switch 27, to the center rail 18, through the clips 19, to the body of the traveling contact point, the pin 17 of the proper button which bears against the body of the contact point, the body of the casing 75 10, and thence to the ground 33, completing the circuit through the ground 32. This will result in an actuation of the armature 25, and by virtue of the arm 29 of the latter, the points 30 will be bridged, which will serve to 80 close the circuit leading to the element 39 which latter may be in the nature of a magnet, coils, etc.

If, on the other hand, the improper button has been pressed, it will be obvious that 85 the head 16 of the pin associated with the same will press against either the outer or inner rail 18. This will result in current passing through the source of supply 31, lead 38, solenoid 22, outer or inner rail 18, 90 and thence grounded as at 33 through the casing 10 completing the circuit through the ground 32.

This action will obviously result in an attraction being exerted upon the armature 24, 95 carrying the arm 26, and upon this occurring it will be obvious that the switch 27 will primarily be opened, subsequent to which the switch 28 will be closed.

This action of closing the switch 28 will 100 result in a completion of the circuit in which the sounding device 35 is arranged, thus actuating the latter. Also by virtue of the opening of the switch 27, it will be appreciated that a subsequent action, before a return of the parts to normal on the part of the solenoid 23, may thus not be accomplished.

To now provide means serving to retain the parts in the position desired by the operator, it will be noted that a suitable latch has 110 been provided, which latch is in the nature of a spring projected slidable pin 39, capable of being retracted by means of a knob 40, extending beyond the outer face of the cover 11. This latch is in line with the body of the 115 armature 25, and upon the latter being retracted against the action of the spring 26, it will be appreciated that the latch will prevent a return of the parts to normal until the pin 39 has been manually withdrawn from 120 out of engagement with the armature 25.

With a view of providing a similar expedient for the armature 24 it will be noted that we may conveniently utilize a bracket 41 within the casing 10, or otherwise render the 125 same suitably inaccessible from the exterior of the same. A spring projected pin 42 is slidably associated with this bracket, and is in line with the body of the armature 22, and arranged at such a position with respect 130

thereto that upon the latter being retracted against the action of its associated spring 26, that a return of the parts to their normal position may not be accomplished until the 5 cover has been opened and the pin 42 manually retracted.

From the foregoing it will be appreciated, reference being had to the preceding paragraphs, that upon the operator having 10 pressed the button 14, that the circuit through the element 39 will have been closed, and an actuation of the same will have been permitted. On the other hand, an opening of this circuit may be effected by a retraction 15 on the part of the knob 40, which will permit the armature 25 to be projected by the spring 26, thus returning the parts to their normal position.

If an unauthorized person operates the device, however, it will be appreciated that in 20 all likelihood he will press the wrong button. This will result in an actuation of the solenoid 22, and armature 24, and any subsequent manipulation of the proper button 14 25 will fail to cause a cessation of operation on the part of the alarm 35, or closing of the circuit through the element 39, for the reason that a return of the armature 24 to its natural position is precluded by the pin 42, thus 30 holding the switch 28 closed and the switch 27 open.

An examination of the foregoing specification, and drawings referred to in the same, will clearly indicate that by means of our 35 improved lock, that we have provided a device which will permit of an operator dispensing with a conventional switch key, at the same time insuring the actuation of an automatic working signal, if an unauthorized 40 person should attempt to close the circuit.

Obviously numerous modifications of structure might readily be resorted to without in the least departing from the spirit of our invention, which we claim as:

1. A lock, including a casing, a switch within said casing for closing a circuit, a secondary switch also within said casing for closing a circuit through an alarm, and 50 further switches arranged in series with said first named circuit, and being adapted to be opened upon an actuation of said secondary switch.

2. A lock, including a casing, solenoids 55 within said casing, armatures associated one with each of said solenoids, and adapted to be operated thereby, switches actuated by said armatures, and means for causing an actuation of one of said solenoids and 60 switches associated therewith.

3. A lock, including a casing, solenoids within said casing, armatures associated one with each of said solenoids and adapted to be operated thereby, switches actuated by 65 said armatures, and a plurality of actuating

means electrically connected with said solenoids.

4. A lock, including a casing, solenoids within said casing, armatures associated one with each of said solenoids, and adapted 70 to be operated thereby, switches actuated by said armatures, a plurality of actuating means electrically connected with said solenoids, one of said actuating means serving to actuate the solenoid operating the switch 75 in series with the main solenoid to be closed.

5. A lock, including a casing, solenoids within said casing, armatures associated one with each of said solenoids and adapted to be operated thereby, switches actuated by 80 said armatures, a plurality of actuating means electrically connected with said solenoids, one of said actuating means being connected with one of said solenoids for causing a closing of a switch, the balance 85 of said actuating means serving, upon actuation, to operate the second solenoid for closing a further switch, and opening a third switch, said last named switch being in series with said last named switch and preventing a subsequent closing of the circuit 90 controlled by the same.

6. A lock, including a casing, a plurality of contact rails within said casing, a traveling contact point arranged upon said rails, 95 a plurality of actuating members arranged above said rails, said contact point being adapted to be borne against by one of said actuating members, solenoids in circuit with said rails, and a source of current supply, 100 armatures controlled by said solenoids, switches controlled by said armatures, one of said switches permitting, upon being closed, of a flow of current through a main circuit fed by said source of current supply, 105 the armature of the second solenoid controlling further switches in series with said source of current supply for causing the actuation of an alarm mechanism.

7. A lock, including a casing, a plurality 110 of contact rails within said casing, a traveling contact point arranged upon said rails, a plurality of actuating members arranged above said rails, said contact point being adapted to be borne against by one of said 115 actuating members, solenoids in circuit with said rails, and a source of current supply, armatures controlled by said solenoids, switches controlled by said armatures, one of said switches permitting, upon being 120 closed, of a flow of current through a main circuit fed by said source of current supply, the armature of the second solenoid controlling further switches in series with said source of current supply for causing the 125 actuation of an alarm mechanism, and the opening of the first named circuit.

8. A lock, including a casing, a plurality 130 of contact rails within said casing, a traveling contact point arranged upon said rails,

4

a plurality of actuating members arranged above said rails, said contact point being adapted to be borne against by one of said actuating members, solenoids in circuit with 5 said rails, and a source of current supply, armatures controlled by said solenoids, switches controlled by said armatures, one of said switches permitting, upon being closed, of a flow of current through a main circuit fed by said source of current supply, the armature of the second solenoid controlling further switches in series with said 10 source of current supply for causing the actuation of an alarm mechanism, the opening 15 of the first named circuit, and means serving to normally retain the first and second switches opened, and last named switch in closed position.

9. A lock, including a casing, a plurality 20 of contact rails within said casing, a traveling contact point arranged upon said rails, a plurality of actuating members arranged

above said rails, said contact point being adapted to be borne against by one of said actuating members, solenoids in circuit with 25 said rails, and a source of current supply, armatures controlled by said solenoids, switches controlled by said armatures, one of said switches permitting, upon being closed, of a flow of current through a main circuit 30 fed by said source of current supply, the armature of the second solenoid controlling further switches in series with said source of current supply for causing the actuation of an alarm mechanism, the opening of the 35 first named circuit, means serving to normally retain the first and second switches opened, and last named switch in closed position, and means for retaining said armatures in retracted position subsequent to 40 their actuation by their respective solenoids.

DILLON HOFFMAN.
FRANK EASTON.
